UNITED STATES PATENT OFFICE.

ROBERT B. HODGE, OF BUFFALO, NEW YORK.

DRAFT DEVICE FOR STEAM-BOILERS.

SPECIFICATION forming part of Letters Patent No. 741,037, dated October 13, 1903.

Application filed June 20, 1902. Serial No. 112,401. (No model.)

To all whom it may concern:

Be it known that I, ROBERT B. HODGE, a citizen of the United States, residing at Buffalo, in the county of Erie and State of New York, have invented new and useful Improvements in Draft Devices for Steam-Boilers, of which the following is a specification.

This invention relates to a draft-producing device designed more particularly for the smoke-stacks of marine boilers; but the same is also applicable to other types of boilers.

The object of my invention is to provide an efficient and economical device of this kind which increases the draft and cools the stack, which can be applied to an ordinary stack without requiring any departure from its usual form or construction, and which at the same time offers as small an obstruction in the stack as possible, so as not to interfere materially with the natural draft when the draft device is not used or becomes temporarily unserviceable.

In the accompanying drawings, Figure 1 is a vertical section through the smoke box and stack of a marine boiler provided with my improved draft device. Fig. 2 is a similar section at right angles to Fig. 1.

Similar letters indicate similar parts in both figures.

A indicates the front smoke box or uptake of the boiler, provided centrally in its bottom with the usual arch A', and B indicates the stack rising from said box.

The draft-inducing device consists of a horizontal fan C, arranged in the lower portion of the stack and secured to a vertical shaft D, which extends downwardly through the smoke-box and the arch A'. This shaft is journaled at its upper end in an open frame or bridge-tree E, secured horizontally within the stack, preferably above the fan, while its lower portion turns in bearings f f', carried by the arch A' and a bracket F, which latter is secured to a shelf F', extending across the base of the arch. The fan-shaft may be driven by an engine or motor of any suitable construction. I prefer to employ a small oscillating steam-engine G, which has its piston-rod g connected with a crank g', secured to the lower end of the fan-shaft. This engine is arranged in the space or recess formed

by the arch A' and the shelf F' and is supplied with steam by a pipe H, having a hand-valve h. A fly-wheel i is applied to the fan-shaft, preferably within said recess. 55

In the use of the device the fan produces a vigorous upward current through the stack, which not only increases the force of the draft, but also cools the stack. It is well known that the efficiency of the draft is impaired by 60 the heating of the stack, and it has been demonstrated that a stack provided with my improved appliance remains comparatively cool, thus maintaining the most favorable condition for an efficient draft. 65

By locating the fan at or near the base of the stack, as shown, it is brought in close proximity to the smoke-box, where it is most effective, and by arranging its driving mechanism outside of and below the smoke-box it 70 is not exposed to the smoke and soot issuing from the stack and not liable to become clogged by the same. This arrangement also renders the apparatus applicable to any ordinary stack without requiring a change or 75 reconstruction of the same.

My improved arrangement has the further important advantage that it permits a practically free and unobstructed draft through the stack regardless of whether the fan is in 80 motion or at rest. This is a desirable feature, as it permits the draft device to be used or not, according to the prevailing conditions of wind and temperature. For example, on a vessel it is desirable to stimulate the draft 85 artificially in quiet or comparatively warm weather, while in cold or windy weather there is little or no occasion for using the draft device, because the natural draft is sufficient.

I am aware that prior to my invention it 90 has been proposed to stimulate the draft through a smoke-stack by one or more fans journaled in the same or in a chamber communicating therewith, and I do not therefore claim, broadly, such an artificial-draft device. 95

I claim as my invention—

1. The combination with the smoke-stack of a steam-boiler, of an upright shaft arranged in the stack and extending downwardly below the base of the same, fan-blades mounted 100 horizontally on the portion of the shaft within the stack, and driving mechanism for said

shaft supported independently of the stack and arranged below the base thereof, substantially as set forth.

2. The combination with the smoke-stack 5 of a steam-boiler, of a bridge-tree arranged in the lower portion of the stack, a vertical shaft arranged in the stack, journaled at its upper end in said bridge-tree and extending below the base of the stack, fan-blades mounted horizontally on the portion of the shaft within the stack, a support arranged below the base of the stack, and driving mechanism mounted on said support and connected with the lower portion of said shaft, substantially 15 as set forth.

3. The combination with a boiler smoke-

stack and a smoke-box provided in its under side with a recess, a shelf extending across said recess, an upright shaft arranged in the lower portion of the stack and extending 20 downwardly through the smoke-box and into said recess, a fan arranged within the stack and mounted on said shaft, and driving mechanism for said shaft arranged in said recess, and supported on said shelf, substantially as 25 set forth.

Witness my hand this 16th day of June, 1902.

ROBERT B. HODGE.
